UNITED STATES PATENT OFFICE.

ERNEST P. DARGIN, OF DENVER, COLORADO.

INTERNAL-COMBUSTION ENGINE.

Application filed July 14, 1922. Serial No. 575,078.

To all whom it may concern:

Be it known that I, ERNEST P. DARGIN, a citizen of the United States, residing at the city and county of Denver and State of Colorado, have invented certain new and useful Improvements in Internal-Combustion Engines; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to internal combustion engines, and more particularly to the construction of the valves thereof.

In the great majority of internal combustion engines manufactured today, the 20 valves are the cam-operated reciprocating valves of well known type.

It is well known that the valves of an internal combustion engine are a source of trouble, as they are constantly becoming foul 25 and must be reground at frequent intervals. They are also usually more or less noisy and very seldom give sufficient port opening to prevent wire drawing of the intake charge and back pressure on the exhaust 30 stroke.

It is the object of this invention to devise a rotary valve that is adapted to be operated from cranks or eccentrics on a rotatable shaft instead of by means of cams. 35 A rotary valve, as is well understood, does not require constant regrounding and reseating, and is also comparatively noiseless, and besides this, it can be so designed as to provide sufficient port opening to prevent wire 40 drawing of the intake and excessive back pressure.

I attain the above objects by means of a construction which I will now describe in detail, reference being had for this purpose 45 to the accompanying drawing in which—

Fig. 1 is a section taken on line 1—1, Fig. 2, with parts thereof broken away to better show the construction:

Fig. 2 is a section taken on line 2—2, Fig. 50 1;

Fig. 3 is a section through the cylinder head taken on line 3—3, Fig. 2;

Fig. 4 is a section taken substantially on line 3—3, Fig. 2, and shows the position 55 of the valves during a portion of the exhaust stroke;

Fig. 5 is a section similar to that of Fig. 4, and shows the position of the valves during a portion of the intake stroke; and

Fig. 6 is a diagram showing the positions 60 of the valves at the various parts of the stroke.

The same reference numerals will be used to indicate the same or similar parts throughout the several views.

Numeral 1 represents a crank casing in which the crank shaft 2 is rotatably mounted by means of suitable bearings 3. Directly above the crank shaft there is a cylinder 4 within which is reciprocably mounted an 70 ordinary piston 5.

A connecting rod 6 joins the wrist pin 7 with the crank pin 8. A timing gear 9, secured to the crank shaft so as to rotate therewith, cooperates with a gear 10 which has a pitch diameter twice 75 that of gear 9. Gear 10 is secured to a crank shaft 11 and serves to rotate the latter at a speed one-half as great as that of shaft 2. The top of the cylinder is a flat surface formed by the upper side of flange 80

12. Bolted to the top of the cylinder block is a cylinder head 13 which contains the valve mechanism, which I will now describe. The cylinder head 13 has an outside wall 14 within which there is a cylindrical housing 15, the inside of which is bored to true 85

cylindrical form and adapted to receive a cylindrical valve which will be hereinafter described. The cylindrical housing 15 is attached at one end to the inside of wall 14 by means of a transverse wall or flange 16. A cap 17 which has an exhaust tube 18 attached thereto, serves to close the opening 90 at the end of member 15 and to direct the exhaust gases into the exhaust pipe. A cylindrical valve member 20 fits within the cylindrical housing with a clearance of approximately one two-thousandths of an 95

inch, so as to rotate freely therein when the parts are well lubricated. A second cylindrical valve 21 fits within the valve 20, and within this last named valve member I insert a third valve member which I will call the "control valve". The control valve has an outer wall 22 which has a sliding fit 100 with the inside of the valve 21; it also has an inner wall 23 which is joined at one end to the outer wall 22 by an annular end wall 24; while at the other end the two walls are held in spaced relation by means of a number of spokes 25, some of which are provided 105

with an opening 26 through which the lubri-

cating oil passes on its way to the inner surface. A central tubular member 27 has the end 28 closed and the other end provided with an outwardly extending flange 29 which is bolted to the removable head A by means of bolts 31. The intake pipe 32 may be bolted to the flange 29 by means of bolts 33. The control valve has a radial ear 33' which is joined by means of a connecting rod 34 to a crosshead 35, which in turn is pivotally attached to the upper end of connecting rod 36. The crosshead 35 is slidably connected with the guides 37. The lower end 38 of connecting rod 36 is connected to a crank pin on the crank shaft 11. Cylindrical valves 20 and 21 are provided respectively with radial ears 39 and 40, to which are respectively connected the upper ends of connecting rods 41 and 42, the lower ends of which are pivotally connected to the crosshead 43 at points 44 and 45, respectively. A connecting rod 46 joins the crosshead 43 with a crank pin 11^a on the crank shaft 11.

As the crank shaft 11 rotates crossheads 35 and 43 are continually reciprocated on guides 37 and 47, through the instrumentality of the crank shaft 11 and the connecting rods 36 and 46. The reciprocation of the cross head 35 is transformed into an oscillating movement of the control valve about the outer surface of tube 27, and causes it to oscillate between the two positions shown respectively in Figs. 4 and 5, which, however, are merely intended to show the approximate extreme positions for the purpose of illustration only. As both valves 20 and 21 are oscillated through the reciprocation of crosshead 43, it is evident that they will be simultaneously moved in opposite directions between the extreme positions which are approximately shown in Fig. 6. Water is admitted to the cooling jacket 48 through pipe 49, and passes upwardly into cooling chamber 19, finally leaving through pipe 50. Oil for lubricating the surfaces of the valve is supplied through pipes 51.

In Fig. 6 I have shown a diagram in which the positions of the valve members 20 and 21 are indicated for the various positions of the engine piston. In this figure the crank shaft is indicated by the circle 2 and numerals 1 to 8 indicate the positions of the crank pin 8 for various parts of the engine cycle, which in a four-cycle engine requires two complete revolutions of the crank shaft. Numeral 11 represents the "cam" shaft or the crank shaft which operates the valves 20 and 21, and the numerals surrounding the same indicate the position of the crank pin 11^a for the corresponding positions of the crank pin 8. Since shaft 11 rotates only half as fast as shaft 2, it will have to make only one revolution per cycle. By the upper concentric circles I have indicated the cylindrical

valves 20 and 21, and the port openings are designated by the letter P.

For the purpose of this illustration, it is presumed that the valve members 20 and 21 are oscillated through an angle of 60 degrees, during which arms 39 and 40 move 30 degrees above the horizontal and 30 degrees below the horizontal line x—x, this, however, is merely illustrative, as the valve may oscillate through greater or less angles. When the parts occupy the positions indicated by numeral 1, the valves 20 and 21 also occupy corresponding positions. The members within the valve 20 designate the position of the right hand side of the port P, while the corresponding numbers below the valves designate the corresponding positions of the port P in valve member 21.

Numerals 1 indicates the position of the parts at the beginning of the power stroke, in which position the valves close the port opening and these remain closed until the parts reach position 3, which is the end of the power stroke. At position 3 the ports P begin to open for the exhaust, and are fully open at point 4, while from 4 to 5 they are closing and are fully closed at 5. At position 5 the crank pin 11^a is in its lowermost position, and from 5 to 1 moves in an upward direction, with the result that the direction of movement of valves 20 and 21 reverses. At point 6 of the intake stroke the valves are again fully open, and close again at 7 and remain closed during the compression and the power strokes. The crank arm which cooperates with connecting rod 36 leads the crank pin 11^a by approximately 45 degrees, and serves to move the control valve in such a manner that the ports are connected to the exhaust and the intake at the proper time, in fact, the control valve is merely, in effect, a two-way valve alternately connecting the ports to the supply and the exhaust pipes.

From the above it is believed the operation of the valves will be clear, and I will not elaborate further on this. An engine built in the manner described will not employ the usual cams which cause noise and which require reciprocating valves which are difficult to keep clean and tight, but instead it employs oscillating valves moved by crank arms or eccentrics, and is therefore capable of much more noiseless operation, and at the same time the valves are not liable to become leaky through the deposit of carbon.

Having now described my invention, what I claim as new is—

1. In an internal combustion engine, an oscillating valve for controlling the intake and exhaust of the engine, comprising in combination, three relatively movable members, means operated by the engine shaft for oscillating said members, two of said

members having simultaneous oscillatory movements in opposite directions.

2. In an internal combustion engine, an oscillating valve for controlling the intake and exhaust of the engine, comprising in combination, three relatively movable members, one of which has two port openings, and the other two having one port opening each, means for moving the one member alternately in opposite directions, and means for simultaneously moving the two members alternately in opposite directions.

3. In an internal combustion engine, an oscillating valve for controlling the intake and exhaust of the engine, comprising in combination three relatively movable members, and means operated by the engine shaft for oscillating said members, two of said members being oscillated simultaneously in opposite directions.

4. In an internal combustion engine, an oscillating valve for controlling the intake and exhaust of the engine, comprising in combination three relatively movable members, and means operated by the engine shaft for oscillating said members, two of said members being oscillated simultaneously and at the same rate in opposite directions.

5. In an internal combustion engine, an oscillating valve for controlling the intake and exhaust of the engine, comprising in combination, three relatively movable members, and means operated by the engine shaft for oscillating said members, one of said members having an intake and an exhaust port, the other two members having each one port opening, and means operated from the engine shaft for oscillating the member having the two port openings, and means for simultaneously oscillating the other two members in opposite directions.

6. In an internal combustion engine having a cylinder, a piston reciprocably mounted therein, a crank shaft, a connecting rod connecting the piston and the crank shaft, and a second crank shaft for operating the valves, said second shaft being driven positively from the first mentioned crank shaft, a cylinder head containing valve means for controlling the intake, compression, power and exhaust strokes, said valve means comprising a supply pipe having one end open and connected with the carburetor and the other end closed, a valve member oscillatably mounted on the supply pipe, said valve member consisting of two cylindrical members concentric with and spaced from each other, a cylindrical member surrounding said valve member and

adapted to oscillate thereon, a second cylindrical member oscillatably mounted on the first named cylindrical member, means connecting the valve member to the second crank shaft for oscillating the same, and means connecting each of the two cylindrical members with the second crank shaft for oscillating the same simultaneously in opposite directions.

7. An oscillating valve for an internal combustion engine, comprising a cylindrical valve housing, an intake pipe extending into said valve housing and concentric therewith, a cylindrical valve member mounted in said cylindrical valve housing, a second cylindrical member mounted within the first named valve member, a third valve member mounted within the second named valve member, said third valve member being composed of two concentric spaced cylindrical members, the smaller of which is movably mounted on the intake pipe, a port opening in said intake pipe, a corresponding opening in said cylindrical member, a single port opening in each of said cylindrical valve members, an exhaust and an intake port in the third valve member, and means for oscillating said members in accordance with the movements of the engine, said valve housing having an exhaust opening in communication with the exhaust port of the valve member.

8. In an internal combustion engine, an oscillating valve for controlling the intake, compression, power and exhaust strokes thereof, said means comprising a cylinder head having a cylindrical chamber extending transversely thereof, an intake pipe projecting into said chamber and of less diameter than the chamber, whereby an annular space is formed, a valve member consisting of two cylindrical concentric members mounted so as to oscillate on the intake pipe and occupying a part of said annular space, a port in said intake pipe, an intake port in said valve member extending from the inside to the outside thereof, an exhaust port extending through the outside of said valve member, a pair of rotatable cylindrical valve members occupying the remaining annular space between the first named valve member and the inner surface of said cylindrical chamber, means for oscillating the valve member, and means for simultaneously oscillating each member of the pair of valve members in opposite directions.

In testimony whereof I affix my signature.

ERNEST P. DARGIN.
